[57] CLAIM

The ornamental design for an automobile cover, as shown and described.

DESCRIPTION

FIG. 1 is a perspective view of an automobile cover showing my new design;

FIG. 2 is a right side view thereof, and the left side is a mirror image thereof;

FIG. 3 is a front view thereof and the rear view is a mirror image thereof;

FIG. 4 is a top view thereof;

FIG. 5 is a bottom view thereof; and,

FIG. 6 is a perspective view thereof showing the cover on an automobile.

The broken line showing of an automobile in FIG. 6 is for illustrative purposes purposes only and forms no part of the claimed design.
